UNITED STATES PATENT OFFICE.

HARRY C. INNES, OF HARTWELL, CINCINNATI, OHIO, ASSIGNOR TO THE PHILIP CAREY MANUFACTURING COMPANY, A CORPORATION OF OHIO.

FLOOR COVERING.

Application filed April 9, 1919. Serial No. 288,870.

To all whom it may concern:

Be it known that I, HARRY C. INNES, a citizen of the United States, and a resident of and whose post-office address is 8360 Burns 5 Avenue, Hartwell, Cincinnati, Ohio, have invented a new and useful Improvement in Floor Coverings, of which the following is a specification.

My invention relates to a new and improved floor covering more particularly adapted for use on concrete, stone, wood, wood block, and similar floors where there is substantially no resilience or flexibility. Many floors, such as concrete floors, are cold 10 or damp, or both, with the result that employees find them very objectionable to stand on, and the employer finds that the efficiency of his men is affected thereby. Concrete floors also give off a fine dust. By my invention I have sought to overcome these objections due to the hardness of the floors, coldness, dampness, lack of resiliency or flexibility, objection to the fine dust and other objections. To do this, I provide a floor covering, which, while I preferably make it as a 15 mat form of manufacture of different sizes, is adapted for use as a floor covering to cover an entire floor. In factories where concrete floors or other hard non-resilient, non-flexible, cold or damp floors are found, it has been noticed that the efficiency of the workmen compelled to stand upon the floor lessens as the day progresses. By means of my improvement, the workman is provided with a 20 mat or a runner or floor covering, which may be placed wherever desired for him to stand on to perform his labor, thereby providing him with a comparatively soft, resilient article upon which to stand, not susceptible to 25 dampness; one that keeps the cold from reaching his feet, and obviates the fine dust which is given off under abrasion due to walking or standing on concrete. In the drawings I have shown my invention in the 30 form of a mat, although I would have it understood that the invention is equally suitable for use as a floor covering to cover the entire floor, stair treads, etc. In the drawings,

Figure 1 is a perspective view of a mat 35 with a portion of the binding cut away.

Figure 2 is an enlarged cross section of a portion of Figure 1.

Figure 3 is a modification of Figure 1.

Figure 4 is a cross section of a modification of a portion of Figure 1.

In the drawings in which like letters relate to like parts, A is the top of the mat, which is preferably made with a relatively thin coating of pure asphalt, or other suitable bituminous material. Of course, if desired, this top or tread surface of the mat may be of any suitable material, such as a layer of suitable design or ornamental bearing material, a veneer of wood, imitation wood, linoleum, oilcloth, canvas, drilling, duck, burlap, paper, felt, etc. B, B, are layers of suitable felt, canvas, drilling, duck, burlap, paper or similar material. I preferably use for these layers B, B, felt saturated with asphalt or other suitable saturating material adapted to preserve the felt and to make same water or moist-proof. Of course, the layers B, B, may each be of the same or of different materials. If desired, the felt, burlap or other material used could be used 55 without saturating, although I find that by saturating the felt or other material (thereby preserving it) that the life of the mat or floor covering is greatly prolonged. C, is a body of bonding material between the two 60 plies B, B,—this bond or body material is any suitable material, plastic or elastic in its nature, preferably a bituminous material, and more preferably an asphalt compound, consisting of an asphalt and other material 65 such as wood fibre, wool fibre, cork, flax fibre, corn stock pith, leather, rubber or any other suitable material, either coated or coated and saturated with asphalt, so as to bond or retain the asphalt and other material, or materials, entering the compound, in a satisfactory plastic body or mass. These layers B, 70 B, and the compound material layer C, are brought into contact in the manufacture of my improved floor covering under pressure, 75 after which, the top layer of asphalt (preferably pure asphalt) is put on. If a more ornamental top surface is desired, any suitable material having a design or color, or 80 ornamentation, may be placed on top, such as the articles referred to above, and others. This same design, or ornamental surfaces 85 may be held in place by any suitable adhesive, or may be held on the covering by the binder hereafter referred to. Either before 90 or after the top layer of asphalt is applied on 95 100 105

a mat, I apply suitable binding D. This binding may be of any suitable material, although preferably I use a metal or a material of a like character, although of course 5 canvas, paper, felt, cloth or material of like character may be used. In placing the metal bindings on the mat I preferably have the edge on the top side at the point E, bent so it projects downward into the top surface of 10 the mat to obviate the possibility of any rough or sharp edges which could in any way mar or mutilate the foot apparel of the person standing or walking thereon, while at the same time, preventing the possibility of 15 any portion of the binding tending to trip the person. On the under side I preferably allow the metal binding portion F, or a part thereof, to be a little below the bottom of the central portion of the mat so it slightly raises 20 this portion of the mat above the surface of the floor.

In the modification shown in Figure 3, I have provided a beveled edge for the mat or covering so that the workman will be less 25 liable to trip or stumble, if he contacts with the edge of the mat, while at the same time affording a slight incline if it is necessary to move any truck or other vehicle over the mat. In Figure 4 I have shown a cross section of a 30 portion of Figure 1 where the binding has been omitted and in which the upper surface is provided with desirable design, color, or ornamental bearing material, a layer or veneer, such for instance as a piece of paper 35 having a design printed thereon; a piece of oilcloth, having a design thereon, or a piece of canvas painted any color, or a wood veneer or imitation wood veneer, etc.

In laying concrete floors in the aisle in front 40 of machines or where the workmen are to stand a sunken portion may be provided into which a runner of my floor covering may be placed, in which event the metal binding D, may be dispensed with.

45 What I claim is:

1. A floor covering composed of a layer of plastic material between two layers of flexible material, and a binding for the edges thereof.

50 2. A floor covering composed of a layer of

plastic material between two layers of flexible, waterproof material, and a binding for the edges thereof.

3. A floor covering composed of a layer of bituminous material and a layer of flexible 55 material compressed together, and a binding for an edge thereof.

4. A floor covering composed of a layer of bituminous material, a reinforcement therefor, and a binding for an edge thereof. 60

5. A floor covering composed of a layer of asphalt compound, a suitable reinforcement therefor, and a binding for an edge thereof.

6. A floor mat composed of two layers of asphalt saturated felt bonded together by a layer of asphalt compound, composed of asphalt and suitable compressible material, a binding therefor, and a tread surface of plastic material. 65

7. A mat composed of two layers of asphalt saturated felt, a bond layer of greater thickness of asphalt compound, a tread surface therefor of suitable plastic material and binding therefor. 70

8. A mat composed of two layers of asphalt saturated felt, a bond layer of greater thickness of asphalt compound, a tread surface therefor of suitable plastic material and metal binding therefor. 75

9. A floor covering composed of a compound of bituminous material and a suitable fibrous filler, a supporting layer therefor, said compound layer being of greater thickness than the supporting layer, and a protective 85 material for the edge thereof.

10. A floor covering composed of a layer of bituminous plastic material containing a fibrous filler, parallel supporting layers therefor, separated by and in intimate contact with said plastic material, and a suitable protective material for the edges thereof. 90

11. A floor covering composed of an asphaltic wearing surface and a supporting 95 layer therefor, and means for protecting the edge thereof.

In testimony whereof, I have signed my name to this specification.

HARRY C. INNES.
